UNITED STATES PATENT OFFICE.

WILLIAM KIRKWOOD, OF CHICAGO, ILLINOIS.

LIQUID-TRANSFERRING APPARATUS.

1,334,542.

Specification of Letters Patent. Patented Mar. 23, 1920.

Application filed July 13, 1918. Serial No. 244,808.

To all whom it may concern:

Be it known that I, WILLIAM KIRKWOOD, a citizen of the United States, and resident of the city of Chicago, in the county of Cook and State of Illinois, have invented certain new and useful Improvements in Liquid-Transferring Apparatus, of which the following is a full, clear, and exact specification.

10 My invention is concerned with liquid transferring apparatus, and is designed to produce a simple and novel structure by which liquid in measured quantities can be transferred from one source or receptacle to another place or receptacle, preferably by means purely automatic in its action.

To this end, in a specific embodiment, it consists of a receptacle or measuring tank having its inlet and outlet ports controlled 20 by check-valves, having in the top an injector co-operating with a valve moved to one position by the liquid in the receptacle when it reaches its maximum quantity and to the other when it reaches its minimum, the 25 valve in the last mentioned position co-operating with the injector to create a vacuum in the receptacle to draw in the liquid, and in the other to create a pressure in the receptacle by which the liquid just drawn in will 30 be forced out.

In a still more specific embodiment, it includes associated with the injector and valve mechanism above referred to, an auxiliary valve in the injector supply pipe, which 35 auxiliary valve is automatically closed cutting off the injector action while the pressure in the tank after the discharge action is completed falls from its maximum to normal, after which the auxiliary valve opens 40 and the injector begins to operate to create a vacuum.

In the preferred embodiment of my invention, as a novel means for delaying the first part of the movement of the valve 45 operating with the injector and accelerating the final portion of its movement, I employ a rubber ring, circular in cross-section, and co-operating with two relatively movable cylindrical surfaces in a manner which will 50 be described in detail.

To illustrate my invention, I annex here-
to a sheet of drawings in which the same

reference characters are used to designate identical parts in all the figures of which—

Figure 1 is a central vertical section 55 through a measuring tank of an apparatus embodying my invention;

Fig. 2 is a central vertical section on an enlarged scale through the valve mechanism associated with the injector;

Fig. 3 is a horizontal section on the line 3—3 of Fig. 2; and

Fig. 4 is a section on the line 4—4 of Fig. 3.

The measuring tank or receptacle 10 preferably takes the form of a cylinder arranged on a vertical axis and having an inlet pipe 11 with a check-valve 12 therein near the bottom on one side, and an outlet pipe 13 likewise near the bottom and conveniently 70 on the opposite side, and having a check-valve 14 therein. The supply pipe 11 may be connected to any convenient source of supply, and I have illustrated the outlet or discharge pipe 13 as connected with a suitable tank or reservoir 15. In the top of the tank 10 is located a generally cylindrical valve casing 16, which is closed at the top by an air-tight cap 17, and is provided at one side with the aperture 18 in which the nozzle 19 of the injector is secured air-tight so that the nozzle of the injector projects some distance inside the valve casing. At the opposite side of the casing and directly opposite to the injector nozzle is an aperture or 85 port 20, with which is preferably associated an injector discharge pipe 21 for reasons which will be subsequently explained.

Associated with the injector is a cylindrical valve member 22, adapted to occupy 90 either the full line position shown in Fig. 2 or the dotted line position, it being moved from one position to the other by the action of the float 23 loosely mounted on the rod 24 depending from the valve 22 and co-operating with the abutments 25 and 26 located at the bottom, and toward the top, respectively, of the rod 24. In the full line position shown in Fig. 2, the injector passage 27 of the valve 22 is opposite to the port 20, and the action of the injector is to suck up the air from the interior of the tank 10, through the ports 28 in the bottom of the valve body 100 and through the passage 29 formed in the

body of the valve and connected with the enlargement 30 around the entrance of the injector passage 27. The action of the injector continues to produce a vacuum in the 5 tank, and as soon as the pressure is sufficiently reduced, the check-valve 12 is raised, and the supply of liquid is drawn into the tank. If the supply be so located that gravity would tend to cause the liquid to flow 10 into the tank, the action of the injector will be to cause the liquid to flow in more rapidly than it would otherwise.

As the liquid rises in the tank, the float 23 rises with it, and when the maximum 15 amount of liquid is substantially reached, the top of the float contacts with the abutment 26 fixed on the rod 24, and eventually raises the rod so as to lift it and carry the valve 22 from the full line position to the 20 dotted line position, the small passage 31 through the top of the valve being provided to prevent the air being compressed in the top portion of the valve casing 16 and thus resisting the movement of the 25 valve. When the valve is thus moved from its full line position to its dotted line position, the injector passage 27 being carried out of register with the outlet 20, which is thus closed, the injector ceases to act as an 30 injector, and the air or other fluid under pressure strikes the back of the passage 29 and passes down through the ports 28 into the body of the tank, putting it under pressure, which increases until the check-valve 35 14 is raised, and the liquid contents are forced out through the passage 13. This movement continues, until the bottom of the descending float 23 contacts with the abutment 25 secured on the bottom of the rod 24, 40 at which time the weight of the float will move the valve 22 from the dotted line to the full line position, thus completing the cycle of movement, and leaving the injector in position to operate as an injector. While 45 I have for convenience illustrated the valve 22 as of a somewhat heavy solid construction, it will be understood that it can be constructed of a light metal as aluminum, and cored out so as not to offer much weight 50 to act in opposition to the lifting force of the water acting on the float 23 or to the weight of the float. Of course the valve 22 might be made of hollow sheet metal construction, provided that the ports and 55 passages described are in effect retained. The top of the passage 29, and the abutment 32 coöperate with the nozzle 19 of the injector to determine the limits of the movement of the valve.

60 In order to secure a somewhat more rapid and certain movement of the valve 22 than would result from the mechanism so far described, I preferably associate therewith the soft rubber ring 33 surrounding the valve, 65 and adapted to rest in the lower position

of the valve in the annular recess 34 formed in the cap 17 and in the upper position in the corresponding annular recess 35 located above the recess 34 a distance equal to the circumference of the ring 33 in cross-section. 70 Between the recesses 34 and 35 is a ridge 36, which produces a contracted passage, and the action of the ring as the valve is moved is as follows: The ring 33 stands in its normal shape in either of the two extreme 75 positions shown, and as the valve 22 rises, the ring is rolled by the lifting movement of the exterior of the valve on the annular surface of the inside of the casing 16, and the ring is in effect turned inside out by 80 this movement, its reversed position being reached when the ring is half way between its two extreme positions, and owing to the natural set of the ring, the rubber resists this movement turning it inside out to the 85 time that the movement is completed, *i. e.*, during the first half of the complete movement of the ring and the valve. During the second half of the movement, when it is being turned from its inside out position to 90 its natural position, the natural tension or torsion of the rubber tends to aid this movement, so that as a result, the action of this ring is to resist and prevent the movement of the valve until the lifting action of the fluid 95 acting through the float 23 is sufficient to overcome the resistance of the ring, after which it moves until it passes the central position, after which the action of the ring causes the valve to move rapidly. This 100 action would occur even if the inner annular surface of the valve casing 16 were of the same diameter throughout and the ring 33 were not compressed, but the compression of the ring caused by the narrowing of the space 105 through which it rolls by the ridge 36 makes an additional resistance to the movement during the first half, and adds that much to the tendency of the valve to move quickly 110 after the central position has been passed. While I might use simply the annular recesses 34 and 35 and the interposed ridge 36 on the surface of the valve casing, I preferably make similar recesses 34^a and 35^b with the interposed ridge 36^a on the surface of the 115 valve 22. While I have shown this mechanism for causing a delayed action during the first half of the movement and an accelerated action during the last half, as applied to this liquid transferring apparatus, 120 it will be understood that it could be used in connection with other apparatus.

While the apparatus thus far described will operate efficiently in the manner described, it will be apparent that during the 125 time the compressed air is escaping after the valve has just been moved to the full line position shown in Fig. 2 until the pressure of the air in the tank 10 is normal, the action of the injector is unnecessary, and results in 130

a waste of compressed air during this period. Unless extreme speed of action is desired, I preferably dispense with the waste of this compressed air during this interval by the following auxiliary valve mechanism: The pipe 21 preferably has its outer end provided with a cylindrical enlargement 37, in which is mounted to slide a perforated disk 38, which has the stem 39 by which it is secured to the cross-head 40 connected to the pair of links 41 which connect it with the parallel cross-head 42. This cross-head 42 is mounted in a space or opening formed in the injector supply pipe 43 by dividing the same at this point in the manner clearly shown in Fig. 2, thus producing the pair of passages 44 for the compressed air around the space in which the cross-head 42 reciprocates. This cross-head 42 is connected to a valve stem 45 which passes through the stuffing box 46 and into the passage of the injector supply pipe 43, where it is provided with a needle valve point 47 designed to co-operate with a valve aperture 48 formed in the injector supply pipe 43. A helically coiled expanding spring 49, of the proper strength, is interposed between the stuffing box 46 and the cross-head 42, and surrounding the valve stem 45, so that it normally holds the auxiliary valve 47 in the full line position shown in Fig. 2 where it does not interfere with the passage of compressed air through the injector supply pipe 43. When, however, the valve 22 is first moved to the full line position shown in Fig. 2, and the tank 10 is full of air under a heavy pressure, say fifty pounds to the square inch, the compressed air rushing up through the ports 28, through the passage 29, and out through the passage 27, it meets with sufficient resistance from the disk 38 so that it moves the disk outward, compressing the spring 49, and moving the needle valve 47 in engagement with the valve aperture 48, thus shutting off the supply of compressed air from the injector. As soon as the pressure of air in the tank 10 has fallen to normal, its action in escaping against the disk 38 is not sufficient to hold the spring 49 under compression, and the spring acts upon the valve 47, allowing the injector to resume its normal action.

While my invention is valuable for transferring many liquids in many different situations, I have designed it more especially for transferring corrosive chemicals, inasmuch as it contains no valve mechanism that need be affected by chemicals or its operation interfered with when they and the parts engaged by the liquids are properly coated, as by lead.

While I have shown and described my invention as embodied in the form which I at present consider best adapted to carry

out its purposes, it will be understood that 65 it is capable of modification, and that I do not desire to be limited in the interpretation of the following claims except as may be necessitated by the state of the prior art.

What I claim as new, and desire to secure 70 by Letters Patent of the United States is:

1. In an apparatus of the class described, the combination with a receptacle having a check-valve controlled inlet and a check-valve controlled outlet for liquids, of an 75 injector applied to the top of the receptacle, and a valve coöperating with the injector thereby alternately to create a vacuum in the receptacle for filling it with liquid and to create a pressure in the receptacle to dis- 80 charge its liquid contents.

2. In an apparatus of the class described, the combination with a receptacle having a check-valve controlled inlet and a check-valve controlled outlet for liquids, of an 85 injector applied to the top of the receptacle, and a valve operated by the rise and fall of the liquid in the receptacle coöperating with the injector thereby alternately to create a vacuum in the receptacle for filling 90 it with liquid and to create a pressure in the receptacle to discharge its liquid contents.

3. In an apparatus of the class described, the combination with a receptacle having a check-valve controlled inlet and a check-valve controlled outlet for liquids, of an injector applied to the top of the receptacle, a float in the receptacle, and a valve operated by but having lost motion connection 95 with the float so that its movement occurs 100 only at the limit of the movements of the float, said valve coöperating with the injector to create thereby alternately a vacuum in the receptacle for filling it with liquid, and a pressure in the receptacle to discharge 105 its liquid contents.

4. In an apparatus of the class described, the combination with a receptacle having a check-valve controlled inlet and a check-valve controlled outlet for liquids, of an 110 injector applied to the top of the receptacle, and a valve coöperating with the injector to create thereby alternately a vacuum in the receptacle for filling it with liquid and a pressure in the receptacle to discharge its 115 liquid contents, an auxiliary valve in the injector supply pipe, and connections with the injector air outlet and said auxiliary valve for closing the latter while the pressure in the receptacle is falling from its 120 maximum to normal.

5. In an apparatus of the class described, the combination with a receptacle having a check-valve controlled inlet and a check-valve controlled outlet for liquids, of an 125 injector applied to the top of the receptacle, a valve operated by the rise and fall of the liquid in the receptacle, coöperating with

the injector to create thereby alternately a vacuum in the receptacle for filling it with liquid, and a pressure in the receptacle to discharge its liquid contents, and means for delaying the first part of the movement of the valve and speeding up the final part of its movement.

In witness whereof I have hereunto set my hand and affixed my seal, this 11th day of July A. D. 1918.

WILLIAM KIRKWOOD. [L. s.]
